UNITED STATES PATENT OFFICE

FRANK C. BURTON, OF CHICAGO, ILLINOIS, ASSIGNOR TO GRIGSBY-GRUNOW COMPANY,
OF CHICAGO, ILLINOIS, A CORPORATION OF ILLINOIS

DESIGN FOR AN ESCUTCHEON PLATE FOR RADIORECEIVER

Application filed February 14, 1929. Serial No. 30,053. Term of patent 7 years.

To all whom it may concern:

Be it known that I, FRANK C. BURTON, a citizen of the United States, residing at 431 South Wabash Avenue, Chicago, Illinois, have invented a new, original, and ornamental Design for Escutcheon Plate for Radioreceiver, of which the following is a specification, reference being had to the accompanying drawing, forming part thereof.

In the drawings:

Fig. 1 is a front elevation view, and
Fig. 2 is a vertical central section.

I claim:

The ornamental design for an escutcheon plate for radioreceiver substantially as shown.

FRANK C. BURTON.
